(57) **CLAIM**

The ornamental design for an endoscopic camera, as shown and described.

DESCRIPTION

FIG. 1 is a front view of an endoscopic camera showing our new design;

FIG. 2 is a top view thereof;

FIG. 3 is a bottom view thereof;

FIG. 4 is a right view thereof;

FIG. 5 is a left view thereof;

FIG. 6 is a cross sectional view taken along line 6-6 of FIG. 3 thereof;

FIG. 7 is a cross sectional view taken along line 7-7 of FIG. 3 thereof;

FIG. 8 is a perspective view showing front, top and left thereof;

FIG. 9 is a perspective view showing rear, bottom and right thereof;

FIG. 10 is a perspective view showing front, bottom and left thereof;

FIG. 11 is an enlarged left view thereof; and,

FIG. 12 is a partial enlarged bottom view thereof.

The broken lines shown in the drawings represent portions of the endoscopic camera that form no part of the claimed design.

1 Claim, 11 Drawing Sheets
